UNITED STATES PATENT OFFICE.

JOHN P. MAHONEY, OF AMSTERDAM, NEW YORK, ASSIGNOR OF ONE-HALF TO MICHAEL J. DONOHUE, OF AMSTERDAM, NEW YORK.

CURTAIN HANGER.

Application filed July 21, 1926. Serial No. 124,008.

This invention relates to means for supporting curtains and has for its object the provision of a light, simple, inexpensive and efficient device whereby a plurality of curtains, portières or valances may be firmly supported without causing any defacement of a window or door frame. The invention is illustrated in the accompanying drawing and will be hereinafter fully set forth.

10 In the drawing:

Figure 1 is a perspective view of one embodiment of the invention as it appears when in use;

15 Fig. 2 is an enlarged detail perspective view of the coupling illustrated in Fig. 1;

Fig. 3 is a view similar to Fig. 1 but showing another embodiment of the invention and illustrating the opposite side of a window frame;

20 Fig. 4 is an enlarged detail perspective view of the coupling shown in Fig. 3;

Fig. 5 is an enlarged sectional elevation, the section being taken on the line 5—5 of Fig. 3.

25 Referring to the drawing more particularly, the numeral 1 indicates a shade roller bracket having an attaching flange 2 at one end through which are formed slots 3 to receive attaching screws 4. It will be understood that the screws 4 are inserted through 30 the slots into the window frame and the provision of the slots permits the bracket to be adjusted upon the frame so that a window shade roller of any length may be accommodated. The bracket 1 is formed with an angular notch 5 in its upper edge whereby it may receive the stationary trunnion of a

35 spring roller in the usual manner, and at the forward extremity of the bracket is an upwardly standing flat-sided spur 7 which is adapted 40 to engage within the channel of a curtain bar 8 and extend upwardly through an opening 9 provided in the base of the channel whereby the bar will be supported. The curtain bar is preferably telescopic in construction, as will be understood upon reference 45 to Fig. 3, in which the bar is indicated as consisting of an outer channel member 10 and an inner channel member 11 slidably 50 and snugly engaged within the outer channel member. The members of the curtain bar are formed with longitudinal corrugations 12 so that they will acquire additional strength and be less apt to buckle under the 55 weight of curtains, valances or portières sus-

pended thereon. The bars also have their end members 13 bent inwardly so as to extend substantially at a right angle to the intermediate portions of the bars and approach the window frame. The ends of the 60 bars are open and in the ends are engaged a coupling member, such as illustrated in Fig. 2. This coupling member consists of a strip of sheet metal or similar material bent into substantially U form presenting 65 an intermediate base member 14 and side members 15 which are adapted to fit closely within the ends of the curtain bars, as shown in Figs. 1 and 3. The side members of the coupling are disposed at a right angle to 70 the intermediate portion 15 thereof so that they will fit within the curtain bars without bending and, when properly assembled, will maintain the bars in parallel spaced relation. The intermediate or base portion 14 75 of the coupling may rest against the window frame and as it is flat and smooth it will brace the structure without defacing the window frame in any way.

80 From the foregoing description, taken in connection with the accompanying drawing, it will be seen that I have provided a very simple and inexpensive but efficient means whereby a plurality of curtain bars may be carried by a single pair of window shade brackets without requiring all the bars to be engaged with the brackets. This arrangement leaves the spaces between the curtain bars entirely clear and thereby facilitates 85 the draping of the curtains, valances or portières according to the taste and desires of the user.

90 In Figs. 3, 4 and 5, I have shown three curtain bars arranged and supported in accordance with my invention, while in Fig. 1 95 the only two bars are supported. In Fig. 3, the shade roller bracket 6 is provided with a spur 7, corresponding in every respect to the spur 7 shown in Fig. 1 and previously mentioned, but, instead of the notch 5, a circular opening 16 is provided to receive the round rotatable trunnion of the shade roller. The bracket 6 is secured to the window frame by screws 17 inserted through slots 18 in an obvious manner. When more than two curtain bars are to be supported according to my invention, the coupling shown in Figs. 1 and 2 is obviously inadequate but I provide the coupling 19 which is of the same general formation, including a back or base member 100 105 110

20 having side members 21 and 22 extending from its ends and being, in addition, provided with an intermediate plate 23 extending from its outer face midway its ends and at 5 a right angle thereto. The several plates 21, 22 and 23 will be engaged in the open ends of the respective curtain bars, as shown in Fig. 3. It will be noted that the plates of 10 the coupling which engage in the ends of the curtain bars are of unequal length. This arrangement permits the couplings to support the curtain bars efficiently even though the curtain bars are all of the same dimensions and, therefore, eliminates the necessity 15 for providing curtain bars having their terminals of unequal length. The couplings may be employed with any of the telescopic, channeled or tubular curtain bars now on the market and will effectually support the 20 same, as illustrated in the drawing.

Having thus described the invention, I claim:

1. Means for supporting a plurality of 25 curtain bars comprising brackets to be secured to a window frame and engaged with an inner bar, and couplings engaged with the ends of said bar and with the ends of a bar disposed in front of and in spaced relation to the bar engaged by the brackets

whereby the outer bar will be carried by the 30 inner bar.

2. Means for supporting curtains and the like comprising brackets to be secured to a window frame, a curtain bar engaged upon and supported by the free ends of the brackets, a second bar disposed in parallel relation to the first-mentioned bar and free thereof, and couplings engageable in the ends of the curtain bars to connect the same and maintain them in fixed spaced relation 40 said couplings and the second bar being entirely free of the brackets.

3. Means for supporting curtains and the like comprising brackets to be secured to a fixed support, a curtain bar engageable upon 45 and supported by the ends of the brackets, other bars disposed in parallel spaced relation to the first bar and free thereof, and couplings consisting of a bridging element and parallel elements extending from the 50 bridging element and engageable in the ends of the curtain bars whereby to connect them in fixed spaced relation the couplings and the last-mentioned bars being entirely free of the brackets and the fixed support. 55

In testimony whereof I affix my signature.

JOHN P. MAHONEY. [L. S.]
